PROCESS FOR TREATING HYDROCARBON
OILS

Jacque C. Morrell, Chicago, Ill., assignor to Universal Oil Products Company, Chicago, Ill., a corporation of Delaware

Continuation of application Serial No. 458,715, May 31, 1930. This application August 11, 1933, Serial No. 684,747. Renewed September 11, 1937

3 Claims. (Cl. 196—48)

This application is a continuation of my application Serial No. 458,715 filed May 31, 1930, which has become abandoned.

This invention relates to cracking hydrocarbon oils and is specifically directed to a process and apparatus in which raw oil charging stock is converted under heat and pressure into various intermediate and final products and the intermediate products are subjected to reconversion under conditions suitable for their maximum conversion into the desired products.

The flexibility of my improved process permits a great variety of operating conditions which depend, in the main, upon the charging stock to be treated and the products desired. For example, a crude oil containing any amount of natural gasoline may be first subjected to topping, the residual products from the topping operation being thence subjected to relatively mild conversion under any desired conditions and various intermediate products from the primary conversion may be subjected to reconversion under conditions best suited for the production of high yields of motor fuel or other desired products. With another type of charging stock, for instance, heavy Mexican residual oil, the flexibility of my process provides for its processing under more ideal conditions. For example, it may be first subjected to mild cracking conditions suitable for converting the least refractory components of oil into the desired products. The residual products from this first operation may then be subjected to various cracking conditions with reflux and/or other intermediate products from the secondary cracking reaction being recycled all or in part back through the same secondary heating element or being recycled, all or in part, and reconverted under different conditions, preferably more severe, in another portion of the system.

In general, my improved process provides a method and means of cracking a great variety of charging stocks under conditions which approach the ideal for the particular oil being treated. More specifically it provides a method and means of cracking charging stocks which are composed of a mixture of hydrocarbons each or several requiring different degrees of cracking and different conversion conditions for their decomposition into high percentages of the most desirable products.

The great variety of operating possibilities provided by my process may be best understood by referring to the accompanying drawings in which Figs. 1 and 2 taken together illustrate diagram-

matically, and not to scale, one form of apparatus suitable for the practice of my invention.

Raw oil supplied through line 1 and valve 2 may be fed by means of pump 3 through line 4, valve 5, line 6 and valve 7 to the flash dephlegmator 8 or may pass in part through valve 9 in line 4 to fractionating tower 10. An alternate arrangement for feeding raw oil which may be used in conjunction with that already described consists in feeding the oil from pump 3 through line 11, valve 12, passing a part thereof through valve 16 directly to coil 17 and the remainder through valves 13 and 53 and line 14 to fractionating tower 15. All of the raw oil may however, pass through valve 16 in line 11 directly into heating element 17.

Heating element 17 is located in any suitable form of furnace 29 and the oil supplied thereto is heated to the desired outlet temperature under the desired conditions and is discharged through line 30 and valve 31 to reaction chamber 32. Vapors from the chamber 32 may pass through line 33, valves 34 and 35 to fractionating tower 10. Unvaporized products from chamber 32 may pass through line 96, valves 97 and 98 into line 26 and thence to heating element 28. Usually higher pressures are employed in heating element 28 than in chamber 32 and in all such cases a pump 36 will be required to feed the unvaporized products from chamber 32 through heating element 28. Pump 36 may be utilized, when required, by opening valves 37 and 38 in lines 39 and 40 respectively, and closing valve 98 in line 96.

Raw oil fed overhead to dephlegmator 8 as described serves to assist fractionation and cooling in this zone and together with the reflux condensate accumulating in the bottom of dephlegmator 8 may pass through line 18 and valve 19 to pump 20 which supplies the hot feed through line 21, valves 22 and 59 in part either through line 14 and valve 53 to fractionating tower 15 or through valve 13 into line 11 and thence to heating element 17 together with such raw oil as may be fed directly thereto. This hot feed from flash dephlegmator 8 may unite in line 14 with that portion, if any, of the raw oil feed from line 11 to fractionating tower 15 and either or both products, thus fed into fractionating tower 15 assist fractionation and cooling in this tower and the unvaporized portions together with reflux condensate from fractionating tower 15 pass through line 23 and valve 24 to pump 25 which supplies the same through line 26 and valve 27 to the heating element 28. Reflux condensate or combined feed, as the case may be, from fractionating 55

tower 15 and unvaporized products from chamber 32 may be combined in varying proportions in line 26 and these combined products or the latter product alone may be fed to heating element 5 28.

Heating element 28 is located in any suitable form of furnace setting 41 and the oil fed through this heating element is raised to the desired conversion temperature under the desired pressure 10 conditions and is discharged through line 42 and valve 43 to reaction chamber 44. Vapors from chamber 44 pass through line 45 and valve 46 to fractionating tower 15, from which vapors pass through line 47 and valve 48 combining in line 15 33 with vapors from chamber 32 and passing therewith through valve 35 into fractionating tower 10.

Reflux condensate from dephlegmator 15 withdrawn through line 23 and valve 24 to pump 25 20 may be fed through line 26 and valve 27 to heating element 28 as already described or any portion of this product may be diverted from line 26 through valve 49 to be fed through line 50 into line 51 and thence to heating element 52.

Reflux condensate from fractionating tower 10 may be withdrawn through line 54 and valve 54' to pump 55 which supplies this oil through valve 56 and line 51 to heating element 52 in combination with that portion, if any, of the 30 products from tower 15 introduced into line 51 as already described. Any portion of the products from dephlegmator 8 may, if desired, be diverted from line 21 through valve 57 and line 58 to combine in line 51 with the rest of the oil fed 35 to the heating element 52.

Heating element 52 is located in a suitable furnace setting 60 and after being heated to the desired conversion temperature at the desired pressure conditions the heated products may be discharged therefrom through line 61 and valve 62 into reaction chamber 44 where they unite with the conversion products introduced to this same chamber from heating element 28 as already described.

Material in chamber 44 then consists of products from both heating elements 28 and 52. Treatment of the vapors from this chamber has already been described. They pass first through fractionating tower 15 and thence through fractionating tower 10 in each of which they are subjected to fractionation, reflux condensate from each zone being withdrawn for further treatment as described. The vapors from the top of fractionating tower 10 which comprise the desired 55 final light product from the system may pass through line 99 and valve 63, may be subjected to condensation in condenser 64 thence passing through line 65 and valve 66 to receiver 67. Undecondensable gas leaves receiver 67 through line 68 and valve 69 while distillate is withdrawn 60 through line 70 and valve 71. If desired, portions of the condensed distillate from receiver 67 may be returned by well known means not shown to fractionating tower 10 or to fractionating tower 15, or in part to each to assist fractionating and cooling in these zones and to maintain the desired outlet temperature at the top 65 of the towers.

Unvaporized residual products from chamber 70 44 which consists of residual portions of the conversion products from both heating elements 28 and 52 may be withdrawn through line 72 and valve 73 and any portion of these products may be removed from the system by means not shown.

75 Preferably these residual products may pass

through valve 74, where the pressure on the residual products is reduced into flash distilling chamber 75. Unvaporized products from chamber 75 may be withdrawn and removed from the system through line 76 and valve 77. Any portion 5 of the reflux condensate from tower 10 may be diverted from line 54 through line 78 and valve 79. This oil may be withdrawn all or in part from the system through valve 80 in line 78, or all or any portion of it may pass through line 81 10 and valve 82 to blend in line 76 with the flashed residual oil withdrawn from chamber 75.

Vapors from chamber 75 pass through line 83 and valve 84 to flash dephlegmator 8 where they are subjected to fractionation, the heavier portions 15 passing through line 85 and valve 86 to be subjected to condensation in condenser 87 thereafter passing through line 89 and valve 90 to receiver 91. 20 Uncondensed gas is released from receiver 91 through line 92 and valve 93. Condensed distillate is withdrawn from receiver 91 through line 94 and valve 95.

Conversion temperatures employed in this process 25 may range from approximately 700° F., to some 1400° F., more or less, and the pressures employed may range from sub-atmospheric to high super-atmospheric pressure of, for instance, 2000 pounds per square inch. It will be understood 30 that different temperature and pressure conditions may be, and preferably are employed in the three different heating elements of the process, the oil preferably being subjected to more severe cracking conditions as it progresses 35 through the various elements. In other words, heating element 17 may employ relatively mild conversion conditions or conditions below those required for substantial cracking for example from 500° F., to 800° F., depending on the character 40 of the oil. Heating element 28 preferably employs liquid phase cracking conditions more severe than those employed in heating element 17, while heating element 52 may employ cracking conditions still more severe than those utilized 45 in heating element 28 for example, vapor phase cracking temperatures upwards of 1050° F. This general rule need not be true in all cases, however.

Pressure conditions throughout the entire system 50 may be substantially equalized. Different pressures are, however, preferably employed in the various systems of the process and differential pressures may be used between the various component parts of the same system.

As a specific example of one type of operation 55 which may be employed in the apparatus above described and the results obtained: a 24° A. P. I. gravity California crude oil containing about 10% of naturally contained gasoline is subjected in heating element 17 to a temperature of about 500° F., under a pressure of about 50 pounds per square inch. A substantial proportion of the crude, including the natural gasoline, is there vaporized in chamber 32 under a reduced pressure of about 60 30 pounds per square inch. The vapors are introduced into secondary fractionating tower 10 also maintained at a pressure of about 30 pounds per square inch.

In this operation the unvaporized oil from 70 chamber 32 is reprocessed in heating element 28 at a temperature of about 850° F., under an increased pressure of about 150 pounds per square inch. Reaction chamber 44 and primary dephlegmator 15 are maintained under a reduced pres- 75

sure of about 60 pounds per square inch and approximately one-half of the reflux condensate from dephlegmator 15 is recycled through heating element 28 and the remainder reprocessed in 5 heating element 52 together with reflux condensate from the tower 10 at a temperature of about 1000° F., under a pressure of about 60 pounds per square inch. Products from heating element 52 are introduced into reaction chamber 44 together 10 with the products from heating element 28. Separation of liquid and vapor occurs in reaction chamber 44, but substantially no liquid level is maintained therein, the liquid being continually withdrawn without accumulation to the flash 15 distilling zone. Vapors from reaction chamber 44 are fractionated in dephlegmator 15 and fractionated vapors from dephlegmator 15 combine with the vapors from chamber 32 and the combined vapors are subjected to fractionation in secondary 20 fractionating tower 10. Reflux condensate from flash dephlegmator 8 is fed in part overhead to dephlegmator 15.

With this type of operation a total yield of 25 about 70% of motor fuel is obtained. This yield is based on the crude oil charged including the 10% of gasoline contained in the charging stock and the gasoline recovered from the flashed distillate. This product possesses anti-knock characteristics rendering it suitable for sale as premium 30 motor fuel. About 5% of pressure distillate bottoms may remain after rerunning the flash distillate and about 18% of residual oil may be recovered from the flash distilling system.

Generally and within limits the higher the temperatures maintained in heating elements 28 and 35 52 the higher will be the anti-knock value of the gasoline produced. The gas yield will also be increased and the temperatures are regulated to prevent excessive gas production unless this is 40 one of the primary aims of the operation.

The process may be operated to produce motor fuel, gas and coke only or the yield of gas and coke may be reduced to a minimum with motor fuel and fuel oil as the principal products.

45 It is obvious that the examples given are illustrative of only a few methods of operating the process of the invention, and hence are not to be construed as limitations upon the broad scope of the invention.

50 I claim as my invention:

1. A process for treating crude oil which comprises heating the crude sufficiently to vaporize light and intermediate fractions thereof and separating the same into vapors and unvaporized oil, fractionating the vapors to separate the intermediate fractions as reflux condensate from the light fractions, subjecting the unvaporized oil to cracking conditions of temperature and pressure, heating the reflux condensate in a heating zone 55 to higher cracking temperature than and then commingling it with the unvaporized oil, separating the resultant mixture into vapors and residual oil, fractionating and condensing the last-named vapors, flash distilling said residual

oil by pressure reduction, fractionating the resultant flashed vapors to condense heavier fractions thereof as flash reflux, retreating a portion of the flash reflux in admixture with said unvaporized oil, supplying another portion of the flash reflux to said heating zone for heating therein in admixture with said intermediate fractions of the crude, and finally condensing the fractionated flashed vapors. 5

2. A hydrocarbon oil conversion process which 10 comprises topping crude oil containing natural gasoline to form a vaporous fraction and a heavier liquid fraction, heating the liquid fraction to cracking temperature under pressure in a heating zone and separating the resultant products 15 into vapors and residue in a separating zone, removing vapors from the separating zone and fractionating the same independently of said vaporous fraction of the crude and out of contact with the crude oil undergoing topping to condense heavier fractions thereof as reflux condensate, returning at least a portion of said reflux condensate to the heating zone for retreatment together with said liquid fraction, combining the fractionated vapors with said vaporous fraction 20 of the crude and fractionating the commingling vapors, cracking reflux condensate formed by the second-mentioned fractionation independently of and at higher temperature than said liquid fraction of the crude and discharging the resultant 25 heated products into the separating zone for separation into vapors and residue therein, and finally condensing the vapors uncondensed in the second-mentioned fractionating step. 30

3. A process for treating crude oil containing 35 natural gasoline which comprises heating the crude sufficiently to vaporize gasoline and heavier fractions thereof and separating the same into vapors and unvaporized oil, fractionating condensing the vapors to form a gasoline distillate 40 and reflux condensate heavier than gasoline, cracking the unvaporized oil in a heating zone under sufficient pressure to maintain a substantial portion thereof in liquid phase and separating the resultant products into vapors and 45 residue in a separating zone, cracking said reflux condensate substantially in vapor phase in a second heating zone at higher temperature than the oil in the first-named heating zone, introducing the heated products from said second zone into 50 the separating zone, removing vapors from the separating zone and fractionating the same independently of the first-mentioned vapors and out of contact with the crude oil and said unvaporized oil to form additional reflux condensate, 55 supplying a portion of said additional reflux condensate to the first-named heating zone for retreatment together with said unvaporized oil, and supplying another portion of said additional reflux condensate to said second heating zone for 60 vapor phase cracking therein together with the first-mentioned reflux condensate.

JACQUE C. MORRELL.
